(57) **CLAIM**

The ornamental design for a boating accessory, as shown and described.

DESCRIPTION

FIG. 1 is a perspective top view of a boat accessory embodying my design, shown mounted on the anti-ventilation plate of an outboard motor for mounting a hydrofoil, trolling motor or trolling plate to show the environment of its use, the anti-ventilation plate and outboard motor, both shown in dotted line, forming no part of the present invention, the apertures shown in dotted line forming no part of the present invention; FIG. 2 is a perspective bottom view thereof, the apertures shown in dotted line forming no part of the present invention; FIG. 3 is a back view thereof;

FIG. 4 is a right side view thereof, the left side view being a mirror image of the right side view;

FIG. 5 is a front view thereof;

FIG. 6 is a top view thereof, the apertures shown in dotted line forming no part of the present invention; and,

FIG. 7 is a bottom view thereof, the apertures shown in dotted line forming no part of the present invention.
